UNITED STATES PATENT OFFICE

103,288

DESIGN FOR A PENCIL SHARPENER

Joseph Ross, New York, N. Y.

Application October 20, 1936, Serial No. 65,381

Term of patent 3½ years

To all whom it may concern:

Be it known that I, Joseph Ross, a citizen of the United States of America, residing in Manhattan, county of New York and State of New York, have invented a new, original, and ornamental Design for a Pencil Sharpener, of which the following is a specification, reference being had to the accompanying drawing, forming part thereof, wherein,

The pencil sharpener is characterized by the dog design as shown, in combination with the pencil sharpener, as shown.

I claim:

The ornamental design for a pencil sharpener, substantially as shown and described.

JOSEPH ROSS.
